United States Patent Office

Des. 196,251
Patented Sept. 10, 1963

196,251

CONTAINER OPENER

Alfred J. Piel, Hubbard, Hardin County, Iowa

Filed Apr. 26, 1963, Ser. No. 74,668

Term of patent 14 years

(Cl. D44—29)

Fig. 1

Fig. 2

Fig. 3

Fig. 4

Fig. 5

I claim:

The ornamental design for a container opener, substantially as shown.
